UNITED STATES PATENT OFFICE.

JOSEPH D. INGRAM, OF AMARILLO, TEXAS.

TRACTOR.

1,375,790.

Specification of Letters Patent. Patented Apr. 26, 1921.

Application filed June 9, 1919. Serial No. 302,670.

To all whom it may concern:

Be it known that I, JOSEPH D. INGRAM, a citizen of the United States, residing at Amarillo, in the county of Potter and State 5 of Texas, have invented a new and useful Tractor, of which the following is a specification.

This invention relates to improvements in tractors, the general object of the invention, 10 briefly stated, being to provide an improved machine capable of independent use for general farm and road work.

A further object of the invention is to provide a unit power and traction plant in 15 which the working parts are entirely inclosed within a protecting housing, and to which housing outside heat may be applied for quickly starting the motor in cold weather or for tempering air when low 20 grade fuels are used.

A further object of the invention is to provide a structure of the character set forth, in which a driven axle is eliminated, and the motor is mounted for rotation, 25 whereby the bearings of the motor may be quickly and accurately adjusted.

A further object of the invention is to generally improve the structure of machines of this character, whereby the weight is 30 properly balanced and the gears so placed as to relieve the frame of strain when power is applied.

A further object of the invention is to provide a wheel carriage at each end of the 35 structure, in which the wheels may be adjusted to different widths and the rear wheel carriage may be shifted laterally independently of the driver and may also be steered independently of the front wheel carriage, 40 and which may be raised to provide high clearance for plowing corn or other high-growing crops.

A further object of the invention is to provide, in combination with a machine of 45 the character set forth, a novel means for shifting the gears from high speed to low speed and vice versa.

With the foregoing and other objects in view, which will appear as the description 50 proceeds, the invention consists in the novel features of construction and combination of parts which will be more fully described hereinafter and particularly pointed out in the claims.

55 In the drawings accompanying and forming part of this specification,

Figure 1 is a side elevation of my improved tractor;

Fig. 2 is a sectional plan view thereof;

Fig. 3 is a longitudinal section of the tractor detached from the front and rear wheel supporting frames, the side bars of the main frame being broken away;

Figs. 4, 5 and 6 are detail perspective views of the gear shift controlling mechanism;

Fig. 7 is a side elevation of one of the disks forming part of the inclosing housing;

Fig. 8 is a side elevation of the two parts of the ring adapted to surround the central opening of the disks;

Fig. 9 is a perspective view of one of the plates which connect the ends of the main frame;

Fig. 10 is a detail perspective view of the 75 pivotal elements by means of which vertical and sidewise movement of the rear frame with relation to the main frame is permitted;

Fig. 11 is a side elevation of a portion of the rear frame, showing the slot for permitting sidewise movement of said frame;

Fig. 12 is a perspective view of the brackets forming the axis around which the tractor housing is mounted for rotation;

Fig. 13 is a detail perspective view showing the reversing gear and the manner in which the same is mounted for movement into and out of engagement with the operating gears; and

Fig. 14 is a perspective view of the 90 depending bracket in which the motor is adapted to be seated.

The same characters of reference designate the same parts in the different figures of the drawings.

Referring to the drawings, the frame of the tractor comprises a pair of U-shaped channel beams 2 connected together at their ends by means of a pair of steel plates 3 and 4, thereby forming a rectangular structure 100 having corner plates 19 for stiffening the structure. Within this frame is mounted for rotation a housing formed of a circumferential tread member 100 secured along its edges to the flanges 101 of a pair 105 of annular members 102, the ends of the housing being closed by a pair of disks 103 having a plurality of openings which are covered by semi-circular lids 104 hinged at their straight sides to the disks and held 110 closed by means of screws around their curved edges, as shown clearly in Fig. 7.

These openings permit access to the mechanism carried within the housing. Brace members or stays 91 are secured at one end to one of the ring members 103 and at their other end to the tread member 100, approximately at the center of its width, such brace members being equally distributed around the circumference of the tread member. Within the housing is secured, by means of brackets 105, a ring member 74 having a double row of internal gear teeth 106, 107.

A pair of sleeve formed bearing members 51, 52 are secured to the beams 2 at opposite sides of the structure, said bearing members having horizontally extending perforated portions 49, 50 adapted to be bolted to said beams, and having arms 55, 56 projecting upward and forward from the horizontal portions 49, 50 respectively, (see Fig. 12). The inner ends of the sleeve portions 51, 52 pass through central openings in the disks 103, around each of which openings is secured by means of rivets or otherwise a two-part ring 108, (Fig. 8), between which and the sleeves raceways are formed for ball bearings 109, (Fig. 3). The sleeve 51 provides a bearing for one end of a clutch shaft 61, the opposite end of which has a bearing in the end of the crank shaft 135, the outer end of the sleeve 51 being closed by a washer member 110 secured by means of screws to the sleeve, in which are inclosed roller bearings 111 between the shaft and sleeve. A hanger bracket 58, provided with upturned ears 112 (Fig. 14), is mounted on the inner ends of the sleeves 51, 52 and is retained thereon by means of rings 60 secured by screws to the sleeves. A motor 54, preferably of V type, is seated in this hanger and secured thereto by means of bolts. The motor flywheel 114 and the usual spring pressed disk clutch 113 are mounted respectively on the shafts 135 and 61 between the motor and one of the ears of the hanger.

For transmitting motion from the motor to the housing, a pinion 63 is splined to the shaft 61 and is in mesh with gear 71 which extends through an opening 115 formed in the sleeve 51, (see Fig. 12), and which gear 71 is fixed to a sleeve 72 that is slidably and rotatably mounted on a shaft 57 secured at its ends in the ends of the angular brackets 55, 56 formed integral with the sleeves 51, 52, (Fig. 12). A pair of gears 75, 76 are loosely mounted on the sleeve 72 and are adapted to mesh respectively with the internal gears 106, 107 carried by the member 74 for high and low speed respectively, the gears 75, 76 being preferably provided with roller teeth, as shown in Fig. 3. The sleeve 72 is provided with a plurality of keyways in which are adapted to slide keys 116 secured to a grooved collar 117, (Fig. 6), which is adapted to receive a yoke for shifting the gears. The keys 116

are provided with projecting keys 118 adapted to slide within keyways formed in the gears 75 and 76, by means of which when the collar 117 is slid, for instance, toward the left as shown in Fig. 3, the keys 118 will engage the low-speed gear 76, whereby the member 74, and thereby the entire housing, is rotated at low speed, while when the collar is shifted toward the right the keys 118 will slide out of engagement with the low-speed gear and into engagement with the high-speed gear 75, thereby causing rotation of the housing at high speed. The sleeve 72 has also formed therein a groove 119 for engagement with a suitable yoke for sliding the gear 71 out of mesh with the pinion 63 when it is desired to reverse the tractor, or for permitting the use of the motor for doing other farm work while the tractor remains stationary. Suitable means is provided for reversing the direction of movement of the tractor. In the present instance this means comprises a U-shaped member 78, one of the legs of which is mount in an opening in a lug 79 formed on the sleeve 51, the other leg carrying a double pinion 77 adapted to mesh with the pinion 63 and the gear 71 when the latter is shifted out of engagement with the pinion 63, whereby reverse motion is imparted to the tractor. The double pinion 77 is normally held out of mesh with the pinion 63 and gear 71 by means of a spring 80 attached to a bracket 81 secured at a suitable point on the sleeve 51. This U-shaped shifting lever 78 is operated by means of a cable that extends over pulleys suitably mounted within the housing. In Fig. 4 is shown the means for operating the gear-shifting and reversing cables. A sleeve bracket 125 is secured by means of a perforated flat portion 126 formed integral therewith to the underside of one of the side members 2 of the frame. Within the sleeve 125 are mounted for rocking movement a plurality of nesting sleeves 110 83, each having secured at each end thereof an arm 127, the arms at one end being attached to the cables leading from the levers at the driver's seat, while the arms at the opposite end of the sleeves extend through an opening 82 formed in the sleeve 52 and are secured to the cables for operating respectively the gear shifting collar 117 and the sleeve 72 and the reversing pinion 77. The opening 82 in the sleeve 52 also permits the passage of the water, gas and intake pipes 84, 85 and 86. A pair of U-shaped channel members 18 are secured to the side beams 2 of the frame and form a support for the hood 17 and gas tank 16, (see Fig. 1).

The front wheels are attached to the frame hereinbefore described for vertical adjustment and also for adjustment as to width. Referring now particularly to Figs. 130

1 and 2, a pair of depending brackets 5 are secured to the front end of the frame and carry at their lower ends bearings in which is mounted a shaft 6, on which are slidably and rotatably mounted a pair of sleeves 7, which are held in adjusted position by means of collars 7' clamped to the shaft 6 by set screws, as shown in Fig. 2. Each of the sleeves 7 carries a forwardly extending rod or arm 8, the opposite end of which is secured in a second sleeve 9, that is slidably mounted on a shaft 10 which forms the front axle of the truck and carries a pair of ground wheels 11. The sleeves 9 are also maintained in adjusted position on the axle 10 by means of collars 9' clamped to the axle by means of set screws. For increasing the distance between the wheels 11 for a furrow guide in plowing, the axle 10 may be removed and a longer axle substituted, as shown in dotted lines in Fig. 2. A pair of tension springs 14 are mounted on an upright spindle 13 which passes through an opening in a horizontal extension of the plate 3 and is supported at its lower end on a cross bar 12 secured at its ends to the arms 8. At the outer end of each of the sleeves 9 may be mounted a spindle 15 carrying a pulley 16 approximately midway of its height around which passes a cable 47 that extends back to the steering wheel at the driver's seat, whereby the front wheels are steered. A vane 17' may be mounted at the upper end of the spindle 15 to indicate to the driver that the front frame has properly responded to the movement of the hand wheel. The usual radiator 70, fan 69 and water tank 64 are mounted on the front end of the frame 2.

40 The fan is operated by means of a belt and pulley connection 68 with a shaft 67 carrying at its rear end a bevel pinion 66 in mesh with a bevel gear 65 secured within a pulley 62 mounted on the end of the shaft 61. The pulley 62 is for the purpose of connecting a belt thereto when the tractor is held stationary and the motor is to be used for doing other work.

45 The rear wheel carrying structure, as hereinbefore stated, is mounted for both vertical and sidewise movement relatively to the main frame. For this purpose I have provided a rear frame comprising a channel-shaped cross bar 26, to the ends of which are secured a pair of extension members 32 provided with a plurality of bolt holes for permitting adjustment of the length of the members 32 on the cross bar 26, whereby the distance between the rear wheels may be varied for road work or plowing. The members 32 are pivoted at their outer ends to a pair of channel-shaped members 29, which are pivoted at their opposite ends to a pair of brackets bolted to the side bars 2 of the main frame, a plurality of bolt open-

ings being formed in the side bars whereby the members 29 may be adjusted along the side bars 2 to correspond with the adjustment of the extension members 32. At the rear ends of the members 29 are pivotally mounted a pair of depending members or standards 130, (Fig. 1), carrying at their lower ends trunnions 131 on which the wheels 33 are mounted. Suitable supporting braces or stays 48 form bearings for the lower ends of the members 130 and are secured at their opposite ends to the members 29. For permitting the rear wheels to be steered independently of the front, the upper ends of the members 130 are provided with a pair of radial arms 132, to the ends of which are pivotally connected a rod 40. A pair of bars 35, one at each side of the frame, are secured at one end to the cross bar 26 and carry at their opposite ends a bar 34, the bars 34 and 35 forming a framework on which is mounted the driver's seat 36 and the attachment-operating levers 37. A shaft 41 is mounted in bearings carried by the bar 34 and the cross bar 26, and on this shaft is secured a chain wheel or sprocket 42, which is connected by a chain 43 to a chain wheel carried on the shaft of the hand wheel 44. The shaft 41 carries a bell crank which is connected to the steering rod 40. The hand wheel shaft also carries a worm adapted to mesh with a worm gear which operates a spool 46 around which the cable 47 for steering the front wheels is wound. The chain 43 may, however, be removed from the sprockets and the rear wheels left to be shifted by a foot lever if so desired. For locking the rear frame to the main frame I have provided a T-shaped member 24, (Fig. 10), which is pivotally mounted on the end beam of the main frame and having the portion 133 thereof extending through an elongated slot 134 formed in the cross bar 26, a roller 25 being mounted on said portion 133 for engagement with the upper and lower walls of said slot, as shown in Fig. 1. An upright spindle 27 provided at its lower end with an eye is pivoted on the outer end of the portion 133, said spindle passing through the connecting plate 4 and having mounted thereon a pair of cushioning springs 28 in a manner similar to the spindles 13 at the front end of the machine. By this construction the rear frame may be maintained against sidewise movement relatively to the main frame by inserting a pin through openings formed in the flanges of the channel bar 26 at each side of the roller 25, thereby preventing the roller from moving sidewise in the slot. A pair of channel formed brace members 20 are secured to the rear portion of the main frame and extend rearward and upward at an angle thereto and carry at their outer ends a pair of uprights 21 for supporting

the hand wheel 44 and the gear shift and clutch levers 22 and 23. A framework 38 is secured to the cross bar 26 for attachment of various farm implements, as for instance listers, plows or cultivators, the latter being illustrated at 39, all of which may be suitably connected with the levers 37 for operation from the driver's seat. I prefer to use in connection with the tractor described the treads 88. Such treads, however, form no part of this invention and are described in my contemporaneously pending application, Serial No. 268,152, filed December 24, 1918.

From the foregoing it will be seen that I have provided a machine in which the motor is mounted in such a manner that its bearings may be adjusted, by releasing the bolts or screws that clamp the hanger bracket to the sleeves 51, 52 and shifting such bracket around its axis to the desired position, the motor having been first disconnected from the gas, water and intake pipes and such pipes reconnected to the motor in its adjusted position. It will also be seen that the motor and the driving mechanism are mounted in parallel relation axially thereof, whereby a better balancing of the weight of the engine is obtained and less strain on the frame is produced when power is applied. It will also be observed that I have provided in this machine a novel means for changing the gears, and while I have described in detail the structure herein illustrated, it is to be understood that I do not thereby limit my invention to the precise features of construction shown, as I am aware that many mechanical changes and modifications may be made therein without departing from the spirit and scope of the invention as set forth in the claims hereto appended.

Having thus described my invention what I claim is:

1. In a machine of the class described, the combination of a frame, a pair of sleeved brackets secured one at each side of said frame, a housing mounted for rotation on the sleeves of said bracket and provided with a double internal gear, a hanger bracket mounted on said sleeves and adapted for adjustment around an axis, a motor seated in said bracket, a shaft mounted for rotation in said sleeves and adapted to be driven by said motor, a pinion mounted on said shaft for rotation therewith, gearing between said pinion and internal gear for transmitting rotary motion to said housing through either internal gear, and means for shifting said intermediate gearing from engagement with one internal gear into engagement with the other.

2. In a machine of the class described, the combination of a frame, a pair of sleeved brackets secured one at each side of said frame and having upwardly extending arms,

a shaft secured in said arms, a housing mounted for rotation on the sleeves of said bracket and provided with a double internal gear, a hanger bracket mounted on said sleeves and adapted for adjustment around an axis, a motor seated in said bracket, a shaft mounted for rotation in said sleeves and adapted to be driven by said motor, a pinion mounted on said shaft for rotation therewith, a sleeve mounted for rotation on said first mentioned shaft, a gear secured to said sleeve and in mesh with said pinion, a pair of gears mounted for rotation on said sleeve and one in engagement with each of said internal gears, and means for securing either of said pair of gears to said sleeve for rotation therewith.

3. The combination as set forth in claim 2, the last mentioned means comprising a plurality of keys adapted to slide in keyways formed in said sleeve and having supplemental keys adapted to slide in keyways formed in said gears.

4. In a machine of the class described the combination with a frame, a housing therein mounted for rotation, and a motor on the frame and within the housing for rotating the housing, of wheel carriages at each end of the machine pivotally secured to the frame and adapted to permit adjustment of the distance between the wheels carried thereby.

5. In a machine of the class described the combination with a frame, a housing therein mounted for rotation, and a motor on the frame and within the housing for rotating the housing, of wheel carriages at each end of the machine pivotally secured to the frame and adapted to permit adjustment of the distance between the wheels carried thereby and the rear wheel carriage shiftable independently of the machine.

6. In a machine of the class described the combination with a frame, a housing therein mounted for rotation, and a motor on the frame and within the housing for rotating the housing, of wheel carriages at each end of the machine pivotally secured to the frame and adapted to permit adjustment of the distance between the wheels carried thereby, the rear wheel carriage being shiftable independently of the machine and adapted to be steered independently of the front wheel carriage, both of said carriages being adapted to be raised with relation to the machine.

In testimony that I claim the foregoing as my own, I have hereto affixed my signature in the presence of two witnesses.

JOSEPH D. INGRAM.
